(57) **CLAIM**

The ornamental design for an expansion valve, as shown and described.

DESCRIPTION

FIG. 1 is a front perspective view of an expansion valve showing our new design;

FIG. 2 is a rear perspective view thereof;

FIG. 3 is a front view thereof;

FIG. 4 is a rear view thereof;

FIG. 5 is a left side view thereof, a right side view being symmetrical to the left side view;

FIG. 6 is a plan view thereof; and,

FIG. 7 is a bottom view thereof.
